UNITED STATES PATENT OFFICE.

ELOF HERMAN MEDÉN, OF ELIZABETH, NEW JERSEY, ASSIGNOR TO A. G. A. RAILWAY LIGHT & SIGNAL CO., INC., OF ELIZABETH, NEW JERSEY, A CORPORATION OF NEW JERSEY.

RAILROAD-CROSSING WARNING-SIGNAL.

1,348,507.

Specification of Letters Patent.

Patented Aug. 3, 1920.

Application filed January 4, 1917. Serial No. 140,554.

To all whom it may concern:

Be it known that I, ELOF HERMAN MEDÉN, a subject of the King of Sweden, residing at Elizabeth, in the county of 5 Union and State of New Jersey, have invented certain new and useful Improvements in Railroad-Crossing Warning-Signals, of which the following is a specification.

10 The present invention relates to improvements in warning signals adapted more particularly for use at railway or other grade crossings, etc., points where vehicle and pedestrian travel require the presence of a 15 signal of this type.

The general use of fast traveling vehicles, such as automobiles, etc., necessitates the provision of signals at danger points, such as crossings at grade; and owing to the high 20 speed of travel, the signal should be of such type as will insure the giving of warning in ample time to permit necessary precautions to be taken.

One of the sources of accidents is provided by the attempts of drivers to pass over grade crossings of railways or other fast moving carriers at the time when such carriers are due to pass the crossing. In cities and towns these crossings are generally protected by gates, etc., under the control of operators who are able to place the barrier in position. However, in suburban or country districts the safety factor of the barrier is not employed, dependence being 35 placed on the usual crossing signs and possibly an audible signal to provide the warning. Obviously, neither is effective in the case of a fast traveling vehicle, since the usual sign simply indicates the presence of 40 the crossing without indicating the presence of imminent danger; and after dark, even the presence of the sign is indicated only in the immediate vicinity of the crossing, at which time any warning effect is 45 valueless to the vehicle driver. Where the audible signal is employed its effective range is so limited as to be valueless excepting to pedestrians and slow-moving traffic.

These general signs are universally used 50 at such crossings, and it is one of the purposes of the present invention to make them real safety factors by the use of mechanism which will produce relative distinctions thereof between periods when safety is pres-

ent and when danger threatens; also to present a precautionary signal visual at a sufficient distance to permit all necessary protective measures to be taken to prevent accidents at such crossings, at distances at which the particular character of the crossing sign cannot be clearly read.

Other objects are to provide a mechanism which can be readily attached to the existing signs; to provide an apparatus of low cost of manufacture and particularly having low 60 maintenance cost; and to provide an apparatus which may be controlled by track circuits so as to produce apparatus operation only when danger threatens.

To these and other ends, the nature of 70 which will be readily understood as the invention is hereinafter disclosed, said invention consists in the improved construction and combination of parts hereinafter fully described, illustrated in the accompanying 75 drawings and more particularly pointed out in the appended claims.

In the accompanying drawings, in which similar reference characters indicate similar parts in each of the views:

80 Figure 1 is a view in front elevation of a signal according to the present invention.

Fig. 2 is a view in side elevation of the same, and showing diagrammatically, certain electrical connections which may be 85 employed.

Fig. 3 is an enlarged vertical sectional view showing a preferred form of lamp and operating mechanism.

Fig. 4 is a detail sectional view.

90 In the drawings, 10 designates a standard suitably supported, on which is mounted any preferred type of warning sign 11, Fig. 1 showing a form now in general use, the sign being located at the top of the 95 standard. This type of structure is well known and is in universal use at grade crossings of railways. While the present invention is equally applicable for use under conditions where the standard is differently 100 arranged, as presently indicated, it is especially adapted as an attachment to the present installations thereby preventing loss of the present installations. The drawings show the invention in the form of an attachment. The numeral 12 designates a housing, secured to the standard in suitable manner, as by strap connections 12^a and, if 105

desired, a supporting arm 12^b, the housing being located at the lower portion of the standard. The housing is provided with a door 12^c affording ready access to the interior of the housing.

- 5 The housing is adapted to receive a removable container 13 carrying acetylene gas under high compression. Leading from the container and detachable therefrom is a 10 tubular connection 14 which extends to a pressure regulator 15 adapted to deliver the gas to a connection 16 under low pressure conditions; 17 indicates a pressure gage mounted in connection 14, this gage being 15 readily inspected when door 12^c is opened, thus enabling an attendant to inspect the state of the container. A suitable stud valve structure 18 is employed to permit the container to be opened to the connections when 20 replacing of containers is desired.

15 The housing and its contents form a source of gas supply to connection 16, the structure permitting replacing of containers when necessary, these containers being adapted to 25 carry a supply of gas sufficient to produce operation of the signal for extended periods.

20 Mounted on standard 10 is an arm 19, which, in the particular installation shown is inclined upwardly, said arm carrying the 30 lamp at its outer end, the lamp being positioned to direct rays of light on to the sign 11. Obviously, the form of the arm or lamp support may vary to meet particular installations, the essential feature being to locate 35 the lamp or source of light opposite the sign and spaced therefrom a distance sufficient to permit proper illumination thereof while the lamp is active.

40 To permit proper direction of the light rays from the lamp on to the sign, I preferably mount the lamp with an approximate universal joint structure. One form of such structure is shown in Fig. 3 in which arm 19 is shown as having its outer end formed 45 with a cup-shaped portion 19^a having an upper annular face 19^b and a lower face 19^c. Face 19^c co-operates with a complementary face of member 20 carried by a spindle 21 projecting downwardly from the base member 22 of the lamp structure. Face 19^b co-operates with an annular flange 22^a carried by base member 22. As is readily understood the co-operation of these parts enables 50 the rotational adjustment of the lamp on a longitudinal axis as well as a shifting of such axis by swinging the lamp in pivotal directions defined by faces 19^b and 19^c. After proper adjustment the parts are secured in position by suitable securing means 55 such, for instance, as nut 21^c threaded to spindle 21.

60 The lamp or source of light is of the type known as "flashers," viz., the gas is supplied to the burner intermittently, a pilot-burner 65 22^b serving to ignite the gas when supplied,

suitable mechanism being employed for controlling the supply of gas to the burner. In Fig. 3, 23 indicates the gas-receiving chamber, one wall of which is formed by a diaphragm structure 23^a, the gas being introduced into said chamber from conduit 16 in an obvious manner. Leading from chamber 23 to the burner 24 is a passageway 24^a, the inlet to which is controlled by a valve 25 suitably supported to move toward and 70 from such passage inlet, said valve having a loose connection with diaphragm structure 23^a, the latter being controlled as to pressure by a suitable spring 23^b.

75 As long as valve 25 remains closed, no gas 80 will pass to the burner and the lamp remains inactive. During such inactivity the gas entering chamber 23 builds up a pressure therein until it moves the diaphragm against the tension of its spring, thus unseating the 85 valve and permitting the gas to reach the burner, reducing the pressure in chamber 23 and permitting the spring to again move the diaphragm to seat the valve, shutting off the 90 gas supply. This provides for intermittent 95 operation—flashing—of the lamp.

This particular structure of gas delivery and supply control is not specifically claimed herein as it is a structure commercially produced.

95 The lamp body is formed with a large opening to receive a lens 26, preferably of clear glass, said lens facing the sign, the light rays from the lens being adapted to illuminate the sign. The body also has 100 another opening in which is mounted a light concentrating lens 27, which may be of any suitable color, red or green, for instance, adapted to produce a more or less distinctive signal. Lens 27 is of a type to project the 105 rays for considerable distances, and is so positioned as to face in the direction of approach of the vehicle or pedestrian; in the drawing the two lenses are shown as being 110 on opposite sides of the lamp.

115 The source of supply is under comparatively high pressure, but through the action of the pressure regulator this pressure is reduced to such an extent that the diaphragm control will be sufficient to control the lamp operation and permit the intermittent illuminating or "flashing" action. The general arrangement thus described provides for intermittent light ray emission through both lenses. As lens 27 is of the 120 light concentrating type adapted to project the rays for considerable distances, and faces the approaching vehicle, it forms a precautionary signal to the driver of the vehicle, informing him of the presence of 125 some danger to be avoided, the "flash" action—the intermittent operation at short intervals—increasing the effect in that the successive flashes will tend to concentrate attention of the driver on to the signal. As the 130

flash is active for considerable distances, ample opportunity is given the driver to reduce speed before reaching the danger point. As the driver approaches, the flash illumination of the sign renders the latter distinctive and easily read, the slow speed brought about by the precautionary signal enabling the sign to be read even though it be of considerable area and contains somewhat lengthy legends.

This action enables the apparatus to be used for other purposes. For instance, it may be employed for calling attention to some particular event or for giving specific instructions or directions, the sign, in such case, carrying the data to be observed. The invention contemplates such use.

However, the invention is more particularly designed for warning at grade crossings, and to render it more effective for this purpose, the apparatus contemplates a control of operation by which the lamp is made active only when danger threatens or when the controlling connections have been arranged in such manner as to make uncertain the operation of such control. In other words, the action contemplated is on the side of safety, viz:—to prevent the flash action only when there is assurance of the absence of danger. While this feature is not absolutely essential and the invention contemplates its omission, its presence is preferred since the "flash" effect on the approaching driver is one of greater significance than where used simply to indicate the presence of a possible point of danger—the flash indicates actual danger conditions.

This result is obtained by the use of control mechanism which renders the lamp inactive under normal or non-dangerous conditions, but which starts the "flash" action whenever a change from the normal takes place.

This inactivity of the source of light is produced by retaining passageway 24^a closed, thus preventing gas from reaching the burner; and when the source is to become active, the passageway is reopened thus enabling the "flash" action to take place until the control mechanism is again actuated, to shut off the supply. It is to be understood, of course, that such supply is cut off for short intervals during the normal operation of the lamp, thus producing the flash effect, but this action differs from the lamp inactivity condition, in that the supply is restored through the normal action of the lamp, while during lamp inactivity, this restoration is brought about by external conditions.

Various ways of providing this control may be employed, Fig. 3 indicating a simple form of apparatus for the purpose. In this view 28 indicates a lever, pivoted at 28^a and carrying a pin or arm 28^b adapted, in one

position, to coöperate with the diaphragm structure to prevent movement of the latter in a direction to unseat valve 25. Lever 28 is held in such position through suitable means such, for instance, as an electromagnet 70 or solenoid, the outer end of the lever having a connection with the solenoid core 29^a.

The solenoid may be of any desired form, but the structure of Figs. 3 and 4 is preferred, in that it is not only inclosed within 75 the lamp body, but is of such form as to permit ready replacement of the coil when necessary.

As will be seen, a coil 29 is employed, this coil having upwardly projecting members 80 or terminals 29^b (Fig. 4), these terminals being adapted to engage pins or connectors 30 projecting through and insulated from the casing, the leads from the source of electrical supply being attached to these pins. Coil 29 85 extends into a pocket 31^a formed in a closure 31 removably secured to the casing, the closure being internally formed to receive solenoid core 29^a within the coil. By removing closure 31, coil 29 can be readily 90 withdrawn, the fingers of terminals 29^b permitting this action to take place. Should, therefore, the coil be damaged or made inoperative in any way, as for instance, through damage by lightning, a new coil 95 may be readily inserted.

As will be clear, energizing of the coil will act to move lever 28 in a direction to form a stop in the path of movement of the diaphragm structure. This action prevents 100 valve 25 from re-opening with the result that pressure in chamber 23 builds up until it equals or exceeds that in conduit 16, thus preventing further supply of gas. This condition will continue until the solenoid is 105 deenergized, whereupon spring 28^c will act to rock the lever on its pivot and remove pin 28^b from its stop position. This permits the diaphragm structure to again operate and unseat valve 25 to start the supply of 101 gas to the burner and effect "flash" action which continues until the solenoid is again energized.

Energizing of the solenoid may be provided in any desired manner, as by manipulation of a switch mechanism. I prefer, however, to provide an automatic control which will provide for lamp activity when danger threatens at the crossing.

One way of accomplishing this result is 120 shown in Fig. 2 in which the control is placed on track circuits, making and breaking or short-circuiting of these circuits controlling the activity and inactivity of the solenoid.

In this view I have shown the solenoid as 125 connected up in a signal bell operating system, such for instance as is employed at the present time at grade crossings, the bell being indicated at 32, its circuit extending from battery 33 to switch 34 (forming the 130

armature of the track relay), lead 32^a, bell 32 and lead 32^b to battery. The track circuit is from battery 35 to track rail 36 lead 37^a, relay 37, lead 37^b, track rail 36^a, to battery. In the absence of a connection between track-rails 36 and 36^a or a break in the circuit connections, relay 37 is operative to move switch 34 to break the bell circuit. The presence of a train or other connection 10 between the track rails, short circuits the relay thus permitting the switch to close the bell circuit and operate the bell.

Where an installation of this type is present, I preferably connect the solenoid in the bell circuit, the circuit being from battery 33 to switch 34, lead 38, solenoid coil 29, lead 38^a, lead 32^b to battery, switch 34 closing this circuit while the relay is energized. Obviously, this circuit may be employed independently 20 of the bell circuit in installations where no audible signal is employed. The combined circuit arrangement enables the signal apparatus now in use to be employed.

It will be understood that the operating 25 means for lever 28 may be reversed, so that said lever is held to render the diaphragm inactive by a spring or weight or other mechanism, and the solenoid structure operative to reverse the position of the lever, 30 this reversal or change being an obvious mechanical change.

As pointed out, the invention is not limited to the specific means employed to control the activity and inactivity of the lamp. 35 While I have shown housing 12 as attached to an installed standard 10, it will be obvious that this housing may form a part of the support for arm 19, by securing the standard to the upper end of the 40 housing, the latter being suitably supported and forming the support for the standard, this being a mechanical expedient which may be employed for new installations without departing from the spirit of the invention.

With the track circuit control in service, the lamp is rendered active only when trains, cars, or engines are within the limits of the track circuit zone, or in the event the 50 track or solenoid circuits become disarranged or damaged. This is advantageous not only because of the fact that knowledge of system operation by the traveling public will cause vehicle drivers, etc., to have assurance that the presence of the "flash" is 55 indicative of actual danger, but also by reason of limiting the use of the gas supply to only such periods of danger, thus materially increasing the length of time each container 60 will remain serviceable before requiring replacement. As the general arrangement is such that continuous use of the flasher entails a cost of but a few cents per week and a replacement of containers at intervals of 65 a number of weeks, it will be apparent that

by so limiting the period of lamp activity the maintenance costs will be further reduced, enabling the apparatus to be installed and operated at low cost, a factor of especial importance in installing systems at 70 the multitude of crossings present in railway systems.

Since each installation carries its own supply of gas, the apparatus can obviously be installed at any point.

As will be seen both lenses of the lamp are active concurrently but the lens action is of a different type, lens 26 being designed simply for illuminating purposes while lens 27 is designed for ray-projection for considerable distances. Since the source of light is positioned opposite the sign and between it and the approaching traffic, and lens 27 is surrounded by non-illuminated portions of the lamp body, the signal produced by lens 27 is made prominent, although the sign illumination produces a lighted zone of diffused light appearance surrounding the lamp and within which the non-illuminated zone produced by the lamp 80 body surrounds the light zone of lens 27. Hence there is no confused effect produced on the approaching traffic by the different forms of light ray emission especially since lens 27 is of the approximately parallel 85 beam type.

While I have herein shown a preferred form of my invention and described various ways in which it may be carried into effect, it will be readily understood that variations 100 and modifications thereof may be required or desired to meet the exigencies of use, and I desire to be understood as reserving the right to make any and all such changes or modifications as may be found desirable or necessary, in so far as the same may fall within the spirit and scope of the invention as expressed in the accompanying claims.

Inasmuch as particular installations may require a spacing of the lamp from the sign 110 a distance greater than may be conveniently provided by the arm 19, it will be understood that the lamp and housing may form part of a structure separate from the sign and its support, such change obviously being a colorable variation from the specific structure disclosed herein, it being readily understood that a change which simply provides a separate support for the housing or lamp will not affect the general principles 115 of the invention disclosed. And while I have herein referred to the arm as being associated with the sign support, it is to be understood that a structure embodying the separate support is considered to be 120 within the meaning of such expression.

What I claim is:

1. As a means for warning traffic, mechanism adapted to produce light signals and illumination in the path of traffic travel, 130

said mechanism comprising a fixedly-positioned legend-bearing sign, and means associated with the sign support for illuminating the sign and for giving a signal of pre-
 5 caution in the direction of approaching traffic, said means including a light-ray projecting device positioned opposite to and having a lens adapted to project light rays directly on the sign to illuminate it, said de-
 10 vice also having a light-concentrating lens facing the direction of approaching traffic, a gas burner within said device and positioned to coöperate with both lenses to produce concurrent precautionary signaling
 15 and sign illumination, and means controllable from a remote point for controlling the activity of the light signals.

2. As a means for warning traffic, mechanism adapted to produce light signals and illumination in the path of traffic travel, said mechanism comprising a fixedly-positioned legend-bearing sign, and means associated with the sign support for illuminating the sign and for giving a signal of pre-
 20 caution in the direction of approaching traffic, said means including a light-ray projecting device positioned opposite to and having a lens adapted to project light rays directly on the sign to illuminate it, said de-
 25 vice also having a light-concentrating lens facing the direction of approaching traffic, and a gas burner within said device and positioned to coöperate with both lenses to produce concurrent precautionary signaling
 30 and sign illumination, and means for rendering said burner active intermittently to produce signals in rapid succession.

3. As a means for warning traffic, mechanism adapted to produce light signals and illumination in the path of traffic travel, said mechanism comprising a fixedly-positioned legend-bearing sign, and means associated with the sign support for illuminating the sign and for giving a signal of pre-
 40 caution in the direction of approaching traffic, said means including a light-ray projecting device positioned opposite to and having a lens adapted to project light rays directly on the sign to illuminate it, said de-
 45 vice also having a light-concentrating lens facing the direction of approaching traffic, and a gas burner within said device and positioned to coöperate with both lenses to produce concurrent precautionary signaling
 50 and sign illumination, said light-concentrating lens being of the approximately-parallel beam type and positioned to produce a distinctive signal within the zone of sign illumination provided by the illuminating
 55 lens.

4. As a means for warning traffic at grade crossings, mechanism for producing light signals and illumination in the path of traffic travel, said mechanism comprising a
 60 grade-crossing legend-bearing sign having

a standard, and means associated with the standard for concurrently illuminating the sign and giving a precautionary signal in the direction of approaching traffic, said means including a light-ray projecting de-
 70 vice positioned opposite to and spaced from the sign and having a burner, a source of gas supply for the burner, a pair of lenses carried by the device opposite the burner, one of said lenses being positioned to di-
 75 rectly illuminate the sign, the other lens being positioned to produce a precautionary signal in the direction of approaching traffic, and means controllable from a remote point for controlling the activity of the light signals.

5. As a means for warning traffic at grade crossings, a signaling unit individual to such crossing and including mechanism for producing light signals in the path of traffic travel, said mechanism comprising a grade-crossing legend bearing sign, means associated with the sign support for concurrently illuminating the sign and giving a precautionary signal in the direction of ap-
 80 proaching traffic, and mechanism for controlling the activity of said means to prevent the illuminating and signaling action when warning action is unnecessary.

6. As a means for warning traffic at grade crossings, a signaling unit individual to such crossing and including mechanism for producing light-signals in the path of traffic travel, said mechanism comprising a grade-crossing legend-bearing sign, means associated with the sign support for concurrently illuminating the sign and giving a precautionary signal in the direction of ap-
 85 proaching traffic, said means including a source of light, and control means for ren-
 90 dering said source active intermittently to produce a succession of "flash" operations, and mechanism for controlling the activity of said means to prevent the illuminating and signaling action when warning action is unnecessary.

7. As a means for warning traffic at grade crossings, a signaling unit individual to such crossing and including mechanism for producing light signals in the path of traffic travel, said mechanism comprising a grade-crossing legend-bearing sign, means associated with the sign support for concur-
 115 rently illuminating the sign and giving a precautionary signal in the direction of ap-
 120 proaching traffic, and control mechanism for limiting the operative periods of said means, said control mechanism being normally operative to restrain means operation whereby absence of means activity will provide in-
 125 dications of crossing safety to the approaching traffic.

8. As a means for warning traffic at grade crossings, a signaling unit individual to such crossing and including mechanism for pro-
 130

ducing light signals in the path of traffic travel, said mechanism comprising a grade-crossing legend-bearing sign, means associated with the sign support for concurrently illuminating the sign and giving a precautionary signal in the direction of approaching traffic, and control mechanism for limiting the operative periods of said means, said control mechanism being normally operative to restrain means operation, said control mechanism including electro-magnetic mechanism operative in said means, and means for controlling the activity of the electromagnetic mechanism.

9. As a means for warning traffic at railway grade crossings, and in combination, a legend-bearing sign positioned on the approach side of the crossing, non-electric means associated with the sign support for illuminating the sign and for giving a precautionary signal in the direction of approaching traffic, and control mechanism active in said means for limiting the operative periods of said means, said control mechanism including a circuit controllable from a remote point, and connections between said circuit and said mechanism whereby the restraint action of the control mechanism will be made ineffective to prevent means operation upon failure of connection operation.

10. As a means for rendering grade crossing signs effective to warn approaching traffic travel, an attachment for concurrently illuminating such sign and for giving a precautionary warning signal to approaching traffic, said attachment comprising an arm carried by the sign support, a light-ray-projecting device positioned by said arm opposite and spaced from the sign, said device including a gas burner, a lens for directly illuminating the sign, and a lens for projecting light rays to a distance in the direction of approaching traffic, a source of gas supply associated with such sign support and operatively connected with the burner, and means controllable from a remote point for controlling the activity of the light signals.

11. As a means for rendering grade crossing signs effective to warn approaching traffic travel, an attachment for concurrently illuminating such sign and for giving a precautionary warning signal to approaching traffic, said attachment comprising an arm carried by the sign support, a light-ray-projecting device positioned by said arm opposite and spaced from the sign, said device including a gas burner, a lens for directly illuminating the sign, and a lens for projecting light rays to a distance in the direction of approaching traffic, a source of gas supply carried by such sign support and operatively connected with the burner, and means controllable from a remote point for controlling the activity of the light signals.

12. The combination with a light-ray projecting device adapted to illuminate signs, said device having a gas burner, and means for controlling the supply of gas to such burner and including a valve structure in the gas path to the burner, of mechanism for limiting the periods when such valve may open, said mechanism including a lever adapted to operate as a stop to prevent valve-opening movement, electro-magnetic means for controlling the periods of stop activity, and means for controlling the activity of said electro-magnetic means.

13. The combination with a light-ray projecting device adapted to illuminate grade crossing signs of railways, said device having a gas burner, a lens structure adapted to project light rays from the burner onto the sign, and means for controlling the supply of gas to the burner, said means including a valve structure in the gas path to the burner, of a circuit controllable from a remote point and mechanism controlled by said circuit for limiting the periods when such valve may open, said mechanism including a lever adapted to act as a stop to prevent valve-opening movement, and a solenoid for controlling the periods of stop activity, said solenoid being operatively controlled by said circuit.

14. The combination with a sign and its support, of an attachment for illuminating the sign comprising an arm carried by such support, and a light-ray projecting device, adapted to project the light rays directly upon the sign, said device having a gas burner, a lens adapted to provide such illumination, said arm being adapted to position the device opposite and spaced from the sign, a source of gas supply, and connections between said source and the burner, said arm and device having a universal joint connection, whereby said device may be adjusted to vary the axis of ray projection.

15. The combination with a sign and its support, of an attachment for illuminating the sign comprising an arm carried by such support, and a light-ray projecting device, adapted to project the light rays directly upon the sign, said device having a gas burner, a lens adapted to provide such illumination, said arm being adapted to position the device opposite and spaced from the sign, said arm and device having complementary means for adjusting the device to vary the axis of ray projection, said means including a hollow member carried by the arm and having substantially concentric annular faces, a base member for the device and having a flange coöoperating with one of said faces, a threaded element carried by the base member and extending through the hollow member, and an element carried by said threaded element and coöoperating with the other of said faces.

16. The combination with a light-ray projecting device having a gas burner, a device frame adapted to protect the burner flame, and means for controlling the supply of gas to such burner, said means including a pressure-controlled valve in the gas path, of mechanism for limiting the periods when such valve may move from its seat, said mechanism including a movable stop structure, electro-magnetic means for controlling movements of the stop structure, and a removable closure for inclosing said magnetic means within the device frame.
17. The combination with a light-ray projecting device having a gas burner, a device frame adapted to protect the burner flame, and means for controlling the supply of gas to such burner, said means including a pressure-controlled valve in the gas path, of mechanism for limiting the periods when such valve may move from its seat, said mechanism including a movable stop structure, electro-magnetic means for controlling movements of the stop structure, and a removable closure for inclosing said magnetic means within the device frame, said electro-magnetic means including terminals carried by the frame and projecting into the frame interior, a solenoid coil seated in a pocket of said closure and having fingers adapted to coöperate with the terminal, and a solenoid core operatively connected to the stop structure.
18. In a signaling apparatus and in combination, a signaling lantern having a main gas burner and a pilot, a renewable source of compressed illuminating gas, a gas conduit leading from said source to the gas burner, an electro-magnetically-controlled valve in said conduit for controlling the flow of gas to the burner and normally operable to cut off the gas flow thereto, and a controllable circuit within which the valve magnet is included, said circuit being unaffected by gas movements, the construction and arrangement of the parts being such that magnet activity to open the gas supply of the main gas burner will be provided upon change in conditions of the controllable circuit.
19. In a signaling apparatus and in combination, a signaling lantern having a main gas burner and a pilot, a renewable source of compressed illuminating gas, a gas conduit leading from said source to the gas burner, a magnetically controlled valve in said conduit for controlling the flow of gas to the burner and normally operating to cut off the gas flow thereto, an electro-magnet for controlling valve operations, and a circuit in
- which said magnet is included, the construction and arrangement of the parts being such that the circuit to the valve control magnet will be completed to open the gas supply to the main gas burner upon change in conditions of the magnet-containing circuit.
20. In a signaling apparatus and in combination, a signaling lantern having a main gas burner and a pilot, a renewable source of compressed illuminating gas, a gas conduit leading from said source to the gas burner, a magnetically-controlled valve in said conduit for controlling the flow of gas to the burner and normally operable to cut off the gas flow thereto, and a circuit within which the valve magnet is included, said circuit being controlled by train movements over tracks with which the signal is concerned, the construction and arrangement of the parts being such that magnet activity to open the gas supply to the main gas burner will be provided upon the passage of a train over such tracks.
21. In a signaling apparatus and in combination, a signaling lantern having a main gas burner and a pilot, a renewable source of compressed illuminating gas, a gas conduit leading from said source to the gas burner, a magnetically-controlled valve in said conduit for controlling the flow of gas to the burner and normally operating to cut off the gas flow thereto, an electro-magnet for controlling valve operations, and a railroad track circuit in which said magnet is included, the construction and arrangement of the parts being such that the circuit to the magnetic valve will be completed to open the gas supply to the main gas burner upon the passage of a train over the track circuit.
22. In signaling apparatus and in combination, a signaling lantern having a main gas burner and a pilot, a renewable source of compressed illuminating gas, a gas conduit connecting the source with the burner, a magnetically-controlled valve in said conduit and normally active as a barrier to prevent passage of gas to the burner, and means whereby said valve is made inactive as such barrier, said means including an electro-magnet operative in the valve control, and a track circuit controlling the activity of the magnet, the construction and arrangement of the parts being such that the burner will be rendered active in the presence of train operations relative to such circuit.

In testimony whereof I affix my signature.

ELOF HERMAN MEDÉN.
